AUTOMATIC CHARGING MEANS FOR
CENTRIFUGAL EXTRACTORS

Jacob J. Neuman, Jamaica, N. Y.

Application October 22, 1935, Serial No. 46,069

12 Claims. (Cl. 210—63)

The present invention relates to automatic charging means for centrifugal extractors, and has for its main object to provide positively acting means for automatically regulating the supply of fill-mass to the extractor. This invention is an improvement over the means disclosed in my Patent 1,921,446. The present regulating means includes the switch actuated by the accumulation of fill-mass as there described but adds thereto an improved gate operating mechanism and additional regulating devices for varying sets of conditions in the operation of extracting the crystals.

Another object is the general simplification of the entire regulating system.

A further object is to provide a regulator system which automatically controls the size of the discharge opening to suit the flow of the fill-mass.

A still further object is to provide a safety means whereby the acceleration of the extractor motor to extracting speed is prevented until the charging of the basket has stopped; also, a warning is given if the charging gate remains open beyond a predetermined time.

Further objects include a means for evenly distributing the fill-mass in the basket, means for manually adjusting the normal opening size, means for manual release of the gate in case of failure of the closing means, and other objects which will become apparent from the following description of one specific embodiment of the device illustrated in the drawings and incorporated into the claims, it being understood that various means may be employed to attain the objects.

In the drawings wherein like symbols refer to like or corresponding parts throughout the several views.

Figure 1 is an elevation partly in section of a centrifugal extractor and charging means embodying the present invention.

Figure 2 is an elevation of the extractor motor controller.

Figure 3 is a detail fragmentary view of the lower edge of the outlet valve gate showing the gate control switch with casing partly broken away.

Figure 4 is an enlarged elevation of the lost motion adjusting device for the gate opening showing parts in dotted lines.

Figure 5 is a circuit diagram of the electrical parts of the device.

Figure 6 is an elevation of a modified form of valve gate showing the release latch, and

Figure 7 is an enlarged transverse section of

the lever arm of the modified gate structure taken through the release latch at the latch pin.

Referring to Figure 1 there is shown a centrifugal extractor of the type employed in refining sugar and in which the revolving basket 10 is enclosed within an outer casing 11 having an inturned top flange 12 on which is mounted the switch 13. A shaft 14 extends downwardly from the switch 13 into the basket 10 and carries at its lower end the finger 15. The upper end of the shaft 14 drives the switch operating mechanism the details of which are disclosed in my aforementioned patent. The extractor basket 10 is mounted on the shaft 16 which is driven by a motor 17 through the pulleys 18, 19 and the connecting belt 20. Fill-mass is supplied to the basket 10 from a suitable hopper discharging through the outlet neck 21. The stream of liquor and crystals discharges onto the improved spreader cone 22 mounted on the shaft. The rotating cone 22 serves to distribute the entering fill-mass in the basket and also to bring it up to the speed of the basket thereby preventing disturbance of the wall of crystals already deposited and unequal loading of the basket. Another advantage to the use of this shaped plate is that fill-mass cannot remain on it, therefore cleaning is unnecessary.

The outlet neck 21 is provided with a gate operated by the pneumatic cylinder 24 and piston 25 connected to the gate by the rod 26, the lost motion adjustment 27 and the eye rod 28 through the eye of which passes a hook or loop 29 fixed to the upper edge of the gate 23. The admission of air into the cylinder 24 is controlled by a system of valves to be explained below.

The extractor motor 17 is controlled by a travelling bridge 30 driven by a pilot motor 31 along a screw 32. At suitable points in the path of the travelling bridge 30 are pivotally suspended mercury switches 13' and 33 to be successively tilted by the fingers 34 of the bridge in its passage towards the "slow" end of the screw 32. Switch 13' is closed in its normal hanging position and serves to energize the holding coil of the switch 13, for description of which see my copending application Serial No. 45,524, filed October 10, 1935. As the extractor motor is retarded the bridge travels to the "slow" end of the screw 32 and the finger 34 tilts switch 13' opening it momentarily and deenergizing the holding coil 80. When the holding coil is deenergized the finger 15 swings to the position shown in Figure 1. The switch 13' is located at a position furthermost to the left of the travel arm

34 so that when the arm 34 reverses and travels to the right it permits the switch 13' to return to its normal position and close circuit and thereby reenergizes the holding coil 80. However, due 5 to the extent of motion of the finger control mechanism the coil has no effect on it.

Next in its retarding direction the bridge finger 34 tilts the switch 33 from its normal open position to closed position, thereby closing the circuit 10 through solenoid 35 swinging the 3-way valve 36 against the normal bias of the spring 37 to open the cylinder feed pipe 38 to the air feed 39.

The air supply line 39 is interrupted by the valve 40 which is controlled by the gate lifting 15 rod 26. A pair of adjustable collars 41, 41 are clamped to the rod 26 in the desired position and spaced relation by any suitable means such as the set-screws 42. The operating stem 43 of the valve 40 is located against the cam surface 20 of the pivoted link 44, is normally biased open or extended by the force of a spring within the valve. The valve is closed by rotation of the link 44 about its pivot 45 on the frame 46 whereby the stem 43 is moved inwardly against its spring. 25 Rotation of the link 44 is accomplished by transmitting the movement of the gate lifting rod 26 thereto. To provide a yielding pick up of the motion of the rod 26 the link 44 is connected between the collars 41 by means of springs 47 30 and connecting chains 48. The distance between the clamps 41 may be adjusted to leave the chains slack and so provide a lost motion take up of the link 44.

A by-pass 49 is provided to cut out the valve 35 40 and in turn is controlled by an electro-pneumatic valve 50. In the discharge of fill-mass from the outlet neck 21 it frequently happens that a large mass of crystals settles out at the discharge opening preventing normal flow therefrom. The normal gate opening as regulated by the lift of the rod 26 is here insufficient to start the flow. To provide for a larger opening the flap 51, as shown in Figure 3, is suspended from the lower edge of the gate 23 in the path of the 45 discharge by a leather or other flexible hinge 52. Affixed to flap 51 is a mercury switch 53 in the circuit of the electro-pneumatic valve 50. In its normal or vertical position the switch 53 is closed energizing the electro-pneumatic valve 50 50 and holding it in its open position. Therefore, although the gate be lifted high enough to close the valve 40 if the flap 51 remain vertical air is still admitted to the cylinder 24 and the raising of the gate continues until the discharge of fill- 55 mass swings the flap, opening the switch 53 and permitting the electro-pneumatic valve 50 to close.

In general operation as soon as the gate 23 is lifted the fill-mass begins to flow, the flap 51 is 60 swung, the electro-pneumatic valve 50 closed and the valve 40 has complete control of the raising of the gate. As the fill-mass begins to flow the accumulated crystals clear the opening and the thinner liquor coming through the large opening 65 tends to fill the basket too rapidly. To reduce the size of the opening to check this destructive flow the cylinder 24 is provided with a needle leak valve 54 allowing the piston 25 and gate control rod 26 to drop until the inside port of 70 the leak valve is covered by the piston. By reason of the lost motion in the springs and chains attaching the link 44 to the rod 26 this lowering of the piston does not open the valve 40 but only takes up the slack and spring.

75 When the accumulation of a layer of crystals

in the basket 10 reaches a thickness sufficient to swing the finger 15 the switch operated by this finger is opened. This switch as shown in Figure 5 is in series with switch 33 and the solenoid 35. As the solenoid 35 is deenergized the 3-way valve 5 36 is permitted to return under the tension of spring 37 to connect the cylinder 24 with the exhaust 55 allowing the piston 25 to drop closing the gate 23 and shutting off the discharge.

A coordinating switch 56 is located on the outlet neck and is operated by the gate 23. An arm 57 on the gate 23 strikes an arm 58 on the switch 56 as the gate descends thus closing switch 56 and starting the pilot motor 31 to increase the extractor motor speed. It will be apparent that such increase of speed will be impossible unless and until the gate 23 closes. This prevents the attainment of extracting speed while the basket is being filled, as for instance, if the piston becomes jammed for any reason holding the gate open. In such a case considerable damage might result if the extractor were to be speeded up. Also on the shaft of the switch 56 is placed a switch 59, as shown in Figure 5, closed as long as the gate remains open and allowing current 20 to flow through the field of a clock 60. If this clock runs past a predetermined time it closes a circuit in a coil 61 closing the switch 62 and passing current through the bell 63 and warning light 64.

Figure 6 shows a safety device for manual release of the gate. The gate shown is a modification of that in Figures 1 and 3 in that the gate 23 is carried by a lever arm 65 which is pivoted at one end to a suitable support near the discharge opening of the outlet neck 21. The free end of the lever 65 is provided with a hand grip 66 and also with the latch 67 connecting the lever to the gate lifting rod 26. The details of the latch 67 are shown in Figure 7 where the lever 65 is cut away at the point where the hooked latch rod 68 passes through it. The hooked inner end of the latch rod 68 passes through the eye of the eye-rod 28 which connects with the lifting rod 26 in the lost motion adjustment 21. The outer end of the latch 45 rod 68 is bent down and provided with a grip 69 by means of which the rod may be turned to disengage the hook from the eye and thus free the gate 23 from the lifting rod 26. The lever 65 may then be swung down by means of the 50 hand grip 66 to close the gate.

In Figure 4 the details of the lost motion adjustment 21 are shown. It consists in a hollow sleeve 70 knurled to provide a good hand grip and having a large cylindrical bore throughout 65 the greater part of its length and a reduced cylindrical bore for the remaining portion. The reduced bore is threaded to receive the threaded end of the gate lifting rod 26 while the larger bore is threaded at its end portion to receive the 70 hollow stop bolt 71 through which passes the eye-rod 28. The inner end of the eye-rod 28 is provided with a head 72 which rests on the upper end of the stop bolt 71 when the lifting rod 26 is raised. When the gate is closed the eye-rod 65 28 moves upwards in the sleeve 70 such movement being limited by the end of the lifting rod 26 threaded down into the sleeve. In order to pick up the eye-rod and the gate the lifting rod must, therefore, move through the free distance between the end of the lifting rod and the top of the stop bolt which distance is adjustable and is varied by turning the sleeve 70 to advance or retract it on the threaded end of the lifting rod 26. This adjustment is employed by the attend- 75

ant to change the size of the discharge opening to suit the rate of flow of the fill-mass.

It is obvious that various changes and modifications may be made in the details of construction and design of the above specifically described embodiment of this invention without departing from the spirit thereof, such changes and modifications being restricted only by the scope of the following claims.

10. What is claimed is:

1. An automatic charge control means for centrifugal extractors having a revolving basket, an extractor motor, and an outlet neck for discharging fill-mass into the basket, comprising a valve 15 for said outlet neck, valve operating means for opening and closing the valve, flow regulating means electrically interconnected between said valve for discharge neck and to the valve operating means and operable by the pressure of the 20 flow of fill-mass to maintain opening of the valve until flow of fill-mass is produced, and independent regulating means connected to the valve operating means to arrest opening of the valve when a predetermined point is reached.

25. 2. An automatic charge control means for centrifugal extractors having a revolving basket, an extractor motor driving the same, and an outlet neck for discharging fill-mass into the basket, comprising a valve for the outlet neck to control the discharge, operating means for said valve, a control for the extractor motor, control means for said valve operating means associated with said motor control to initiate the opening of the valve when the extractor motor is controlled to 30 a low speed suitable for the discharge of fill-mass and means engageable with the valve upon movement thereof to closed position to regulate said control for said extractor motor.

3. An automatic charge control means for centrifugal extractors having a revolving basket, an extractor motor, and an outlet neck for discharging fill-mass into the basket, comprising a valve for said neck, operating means for the valve, feeler means within said rotating basket indicating the thickness of accumulated fill-mass on the side walls of said basket, regulating means for said extractor motor, control means for the valve operating means associated with said feeler means and with said motor regulating means 45 opening the valve at a definite extractor motor speed and closing the valve when a definite thickness of fill-mass accumulates on the walls of the extractor basket and means disposed in the path of the movement of said valve to closed position 50 to control said extractor motor regulating means.

4. An automatic charge control means for centrifugal extractors having a revolving basket, an extractor motor, an outlet neck for discharging fill-mass into the basket, comprising a valve for 55 said discharge neck, operating means for said valve, regulating means for said extractor motor, coordinating means preventing advance of the regulating means to increase extractor motor speed while said valve remains open, and time controlled means electrically connected with said valve and initiated on opening of said valve warning of prolonged open condition of the valve.

5. An automatic charge control means for centrifugal extractors having a revolving basket, an extractor motor, and an outlet neck for discharging fill-mass into the basket, comprising a valve for said discharge neck, operating means arresting the opening of said valve when a predetermined position is attained, and an opening 70 restricting means connected with the operating

means partially reducing the valve opening after the arrest by said control to compensate for increase in flow of fill-mass after free flow has started.

6. An automatic charge control for centrifugal extractors having a revolving basket, an extractor motor driving the same, and a discharge neck for discharging fill-mass into the basket, comprising a gate valve for said discharge neck, fluid operated means for opening and closing said gate, a fluid supply line for said fluid operated means having a control valve for said means and having fluid admission and exhaust positions to admit fluid to or exhaust fluid from said opening and closing units, an extractor motor controller, a switch on said controller for said control valve admitting fluid to said opening and closing means to initiate the flow of fill mass into the basket when the extractor motor is controlled to a predetermined speed and to thereby maintain said gate valve in open position, a shut-off valve interposed in the fluid supply line operating to close said line when a definite gate height is reached, a flap positioned to hang across said discharge neck in the path of the fill-mass when said gate is open, a flap operated switch on said flap opened by the discharge of fill-mass, a by-pass fluid line around said shut-off valve, an electrically controlled valve in said by-pass line in the circuit of said flap switch and closed by opening said flap switch, a gate control switch on the extractor in series with said controller switch, a feeler in the extractor basket opening said switch upon accumulation of a layer of fill-mass of predetermined thickness on the walls of the extractor basket closing the control valve, stopping the admission of fluid to the gate operating means and exhausting the same allowing the gate to close, and a coordinator switch on the discharge neck preventing advance of the motor controller 40 until the gate is closed.

7. An automatic charge control means for centrifugal extractors having a revolving basket, an extractor motor and an outlet neck for discharging fill-mass into the basket, comprising a valve for said discharge neck, controlling means for opening and closing said valve, feeler means in said extractor basket connected to said controlling means closing the valve when a definite thickness of fill-mass accumulates on the walls of said basket, a downwardly flaring distributor plate revolving with the basket and in the path of the discharging fill-mass, a rod connecting said valve controlling means with said valve, a lost motion connector between said rod and said valve, and regulating means for said opening and closing means preventing opening of the valve with the extractor motor at high speed.

8. An automatic charge control means for centrifugal extractors having a revolving basket, an extractor motor and an outlet neck for discharging fill-mass into the basket, comprising a gate on said neck, operating means for opening and closing the gate including an operating rod, a manually releasable latch on the gate, an adjustable lost motion connector between said operating rod and the latch providing various gate openings and automatic controlling means for said gate operating means coordinating gate opening and extractor motor speed.

9. An automatic charge control for centrifugal extractors having a revolving basket, an extractor motor driving the same, and a discharge neck for discharging fill-mass into the basket, comprising a gate valve for said discharge neck,

fluid operated means for opening and closing said gate, a fluid supply line having a control valve for said means and having fluid admission and exhaust positions, an extractor motor controller, a switch on said controller for said control valve admitting fluid to said opening and closing means to open the gate when the extractor motor is controlled to a predetermined speed, a shut-off valve interposed in the fluid supply line controlled by the movement of the gate or the gate rod thereof operating to close said line when a definite gate height is reached, a flap positioned to hang across said discharge neck in the path of the fill-mass when said gate 10 is open, a flap operated switch on said flap opened by the discharge of fill-mass, a by-pass fluid line around said shut-off valve, an electrically controlled valve in said by-pass line in the circuit of said flap switch and closed by opening said 15 flap switch, a gate control switch on the extractor in series with said controller switch, a feeler in the extractor basket opening said switch upon accumulation of a layer of fill-mass of predetermined thickness on the walls of the extractor basket closing the control valve, stopping the admission of fluid to the gate operating means and exhausting the same allowing the gate to 20 close, a coordinator switch on the discharge neck preventing advance of the motor controller until 25 the gate is closed, a second switch on the discharge neck closed as long as the gate remains open, and electrically operated time warning means connected to said second switch and initiated upon closing of said second switch to give 30 notice if the gate remains open beyond a predetermined time.

10. An automatic charge control means for centrifugal extractors having a revolving basket, an extractor motor, an outlet neck for discharging fill-mass into the basket, comprising a gate 35 on said neck, operating means for the gate including an air operated cylinder, a piston having a rod attached to the gate, an air supply and exhaust valve for said cylinder acting to cause 40 opening and closing of said gate and controlled 45

by the speed of the extractor motor, a feeler in said basket to gauge the amount of fill-mass therein, a shut-off valve in the air supply line having a control arm in the path of the piston rod and moved by the rod to close the valve at a definite piston position, a by-pass air pipe around said cut-off valve and provided with a by-pass valve, a flap operated switch controlling said by-pass valve to open said by-pass valve in the absence of a flow of fill-mass, and a bleed 10 valve in the cylinder and having an internal port opening inside the cylinder at a point before the piston position operating the cut-off valve allowing a return of the piston until it covers the port of the bleed valve. 15

11. An automatic charge control means for centrifugal extractors having a revolving basket, an extractor motor and an outlet neck for discharging fill-mass into the basket, comprising a valve for said discharge neck, operating means for said valve, regulating means for said extractor motor for shifting said extractor motor from low to high speed, and means connected with said regulating means and engageable with said valve upon movement thereof to closed position to thereby affect said regulating means in a manner to increase the extractor motor speed from a low charging speed to a high speed when said valve has been moved to a completely closed 20 position. 25

12. An automatic charge control means for centrifugal extractors, having a revolving basket, an extractor motor, and an outlet neck for discharging fill-mass into the basket, comprising a valve for said discharge neck, a rod connected to said valve, valve operating means connected to said rod, a control member for said operating means, an operating member for said control member having a portion therof projecting in the direction of said rod, and means carried 30 by said rod engageable with the projecting portion of said operating member to thereby control the operation of said valve operating means. 35
